(57) **CLAIM**

The ornamental design for the atomizing nozzle, as shown and described.

DESCRIPTION

FIG. 1 is a perspective view of the atomizing nozzle;
FIG. 2 is a left side view of the atomizing nozzle;
FIG. 3 is a front view of the atomizing nozzle;
FIG. 4 is a top view of the atomizing nozzle;
FIG. 5 is a right side view of the atomizing nozzle;
FIG. 6 is a rear view of the atomizing nozzle; and,
FIG. 7 is a bottom view of the atomizing nozzle.
The broken line showing is for illustrative purposes only and
forms no part of the claimed design.
